Frederick Curtis

United States Patent Office.

S. A. CHASE, OF BOSTON, MASSACHUSETTS.

Letters Patent No. 70,411, dated November 5, 1867.

IMPROVED ELASTIC SASH-ELEVATOR.

The Schedule referred to in these Letters Patent and making part of the same.

TO ALL TO WHOM THESE PRESENTS SHALL COME:

Be it known that I, S. A. CHASE, of Boston, in the county of Suffolk, and State of Massachusetts, have invented a new and useful Improvement in the Method of Elevating Window-Sashes; and do hereby declare the following to be a full, clear, and exact description of the same, due reference being had to the accompanying drawings, making part of this specification, and in which—

Figure 1 is a vertical central and longitudinal section, and

Figure 2 a vertical central and transverse section of a window-frame and sashes provided with my invention.

Figure 3 is an edge elevation of one of such sashes.

The object of this invention is to provide a simple economical device for elevating window-sashes, and one which may be readily applied to old houses unprovided with any means to accomplish this end, and which have no recesses in the window-frame to receive the ordinary cords and weights employed in modern houses.

The invention consists in combining with the window-frame and sash or sashes two or more elastic cords, one end of which is fixed to a convenient part of such frame, and the other to the sash, in such manner that the elasticity of such cord shall elevate the sash or sashes after being depressed.

In the accompanying drawings, A denotes a window-frame containing two sashes B C, made and applied together in any well-known or usual manner. The outer edges of each sash are grooved or channelled, as shown at *a a*, &c., for réception of an elastic cord, *b* or *c*, which is laid within such groove, and confined to the lower end of such sash by any proper device which allows it to be readily removed from connection with such sash. The opposite ends of such elastic cord are secured to the upper inner edge of the window-frame, in juxtaposition with the edge of the sash, and in the same manner as the cord is secured to the sash, which consists, in the present instance, of loops *d d*, formed upon each end of such cord, these loops being passed over screws or studs *e f*, applied respectively to the edge of the sash and to the window-frame, as represented in the drawings. The mode of applying the elastic cord, however, may be considerably varied without affecting the character of my invention. Each sash is to be provided with a suitable device for locking it at any desired altitude. Upon releasing or removing the pressure of such lock or catch, the lower sash will be raised automatically by the reactive power of the elastic cord. The upper sash, upon being lowered to the desired extent, is to be locked in such position against the reactive power of the elastic cord. Upon releasing the hold or pressure of the lock, such sash will be automatically raised to its normal position.

The invention is intended principally for application to railway cars, and, as before observed, to old houses unprovided with any means of raising the sashes, although its economy of construction and ease of application and renewal when worn or destroyed render its employment in any situation valuable.

The only operation necessary to apply it is to rebate one or both edges of the sash, and to fix the screws or studs in proper position. By means of the loops upon each end of the elastic cords, these cords may be applied instantly. Should they become worn, or lose their elastic properties, new ones may be substituted by any one with little pains. For railway-car windows or other small windows, a cord upon one edge may be found sufficient.

I claim the mode of elevating window-sashes by means of elastic cords, substantially in manner and for the purpose as described.

S. A. CHASE.
